UNITED STATES PATENT OFFICE.

HUEY EDWARD GASSAWAY, OF FLOYD, TEXAS.

STAY-HINGE.

1,093,843.

Specification of Letters Patent. Patented Apr. 21, 1914.

Application filed May 8, 1913. Serial No. 766,303.

To all whom it may concern:

Be it known that I, HUEY EDWARD GASSAWAY, a citizen of the United States, residing at Floyd, in the county of Hunt and State 5 of Texas, have invented certain new and useful Improvements in Stay-Hinges, of which the following is a specification.

This invention relates to hinges having a stay for supporting the lid or cover of a tool 10 chest, trunk or the like, in open position, to prevent the hinge from being broken.

It is the object of the invention to provide an improved stay-hinge which is simple in construction and inexpensive to manufacture, and which can be readily applied. The stay is so constructed and arranged that it folds close to the wall of the chest or trunk when the lid is closed, leaving no projecting parts to take up room or liable to be broken.

20 In the accompanying drawing, Figure 1 is a rear end view of a fragment of a tool chest equipped with my improved stay-hinge. Fig. 2 is a cross-section on the line 2—2 of Fig. 1. Fig. 3 is a cross-section 25 showing the lid of the chest swung open. Fig. 4 is a plan view showing the blank out of which the hinge members are formed. Fig. 5 is a perspective view showing a modified form of flange. Fig. 6 is a perspective 30 view showing the blank out of which the hinge illustrated in Fig. 5 is formed.

Referring specifically to the drawing, the hinge comprises two leaves 5 and 6, respectively, each of which is a flat metal plate 35 having apertures along its edges for suitable fasteners whereby they are secured to the chest 7 and the lid 8, the leaf 5 being secured to the lid, and the leaf 6 to the chest. The leaf 5 has a tongue at one end which is 40 rolled into a hinge knuckle 9, and the leaf 6 has two tongues at one end which are rolled into hinge knuckles 10 between which the knuckle 9 fits. A pin 11 passing through the knuckles 9 and 10 completes the hinge 45 joint. The end of the leaf 5, opposite the end having the hinge knuckle 9, has a tongue which is rolled into cylindrical form to serve as a bearing or pivotal support 12 for one end of the stay 13. The end of the leaf 50 6 opposite the end having the hinge knuckles 10 has a tongue 14 of the same width as the tongue forming the bearing 12. This tongue 14 is bent over to extend parallel to the face of the leaf 6 in spaced relation 55 therewith, and has at its extremity a lip 15, which is bent down and passed through a

slit 16 in the leaf 6 and clenched on the under side thereof, whereby the tongue is held rigid in spaced relation with the leaf.

The stay is in the form of a link and is 60 made out of wire. The side bars of the link are bent inward at one end, as indicated at 17, to form journals which extend into the bearing 12. The cross bar 18 connecting the other ends of the side bars of the link 65 is slidably mounted on the leaf 6 under the bent over tongue 14, the latter providing a slot in which the cross-bar works. Intermediate their ends, the side bars of the link have an outward bend 19 to clear the hinge 70 knuckles of the leaves 5 and 6, when the lid 8 is closed. Thus, the stay lies close to the hinge leaves when the lid is closed, and there are no projecting parts liable to injury or taking up space. When the lid 8 is 75 swung open, the cross-bar 18 slides down under the tongue 14 until it reaches the end thereof. In this position, it extends diagonally between the lid and the chest, and serves to brace the hinge and prevent the 80 same from being broken by the weight of the lid. Upon closing the lid, the cross-bar slides back under the tongue 14, and when the lid is entirely closed, the link lies close 85 to the hinge leaves, the parts 19 fitting over the hinge knuckles. The width of the parts 12 and 14 is less than the width of the hinge leaves, so that the stay, when folded, lies 90 against the face of the hinge leaves near their edges.

Figs. 5 and 6 show a slightly modified form of hinge, in which each one of the leaves 5 and 6 has two hinge knuckles 20, and the leaf 6 has a tongue 21 serving the same purpose of the tongue 14. The tongue 95 21 has a lateral enlargement 22 at its outer end, and is bent over in the same manner as the tongue 14 for the same purpose, the extremity of the tongue being fastened down on the face of the leaf by securing the enlarged portion 22 to the latter.

I claim:

A stay hinge comprising a pair of hinged leaves, and a stay extending therebetween, one of the leaves having at its end which is 105 opposite its hinged end a bearing, and the corresponding end of the other leaf having an integral tongue of a width less than that of the leaf, which tongue is bent to extend in spaced relation with the outer face of said 110 leaf and connected at its end thereto, the stay being a link having parallel sides and

cross bars connecting the ends thereof, one of said cross bars being journaled in the aforesaid bearing and the other cross bar being slidably mounted on the second-mentioned leaf under the bent over tongue thereof, the width of the link being less than the width of the hinged leaves, and the intermediate portions of the sides of the link hav-

ing bends to clear the hinge connection of the leaves when the link is folded.

In testimony whereof I affix my signature in presence of two witnesses.

HUEY EDWARD GASSAWAY.
